GARMENT HANGER BAR

Carl E. Gingher, 304-328 Depot St.,
Scranton, Pa. 18509

Filed Feb. 3, 1969, Ser. No. 15,601

Term of patent 14 years

Int. Cl. D6—99

U.S. Cl. D33—8

FIG. 1

FIG. 2

FIG. 3

FIG. 4

FIG. 1 is a front elevational view of a garment hanger bar showing my new design;

FIG. 2 is a fragmentary front elevational view of one end thereof;

FIG. 3 is a fragmentary rear perspective view of the end shown in FIG. 2; and

FIG. 4 is an end elevational view thereof.

I claim:

The ornamental design for a garment hanger bar, as shown.
